UNITED STATES PATENT OFFICE.

CHARLES ADELBERT WARD, OF WATERBURY, CONNECTICUT.

ADVERTISING-CLOCK.

SPECIFICATION forming part of Letters Patent No. 429,552, dated June 3, 1890.

Application filed November 25, 1889. Serial No. 331,504. (No model.)

To all whom it may concern:

Be it known that I, CHARLES ADELBERT WARD, a citizen of the United States, residing at Waterbury, in the county of New Haven 5 and State of Connecticut, have invented certain new and useful Improvements in Advertising-Clocks; and I do hereby declare the following to be a full, clear, and exact description of the invention, such as will enable others skilled in the art to which it appertains 10 to make and use the same.

My invention relates to certain novel and useful improvements in machines for displaying advertisements, and which are preferably 15 incased with a clock or music-box for the purpose of attracting attention—such, for instance, as shown in patent to Woolverton, No. 392,939, November 13, 1888; and the objects of my invention are to furnish a simple 20 and positive construction for the tumblers, which are located at the sides of the case; to furnish positively-operated mechanism for the actuation of said tumblers; to furnish means for assisting the drop of the advertising 25 sheets or leaves which are at the central portion of the machine; and with these ends in view my invention consists in the details of construction and combination of elements hereinafter to be fully set forth, and then referred 30 cited in the claims.

In order that those skilled in the art to which my invention appertains may fully understand its construction and method of operation, I will describe the same in detail, reference being had to the accompanying drawings, 35 which form a part of this specification, and in which—

Figure 1 is an elevation of the complete machine, the front of the case being removed; 40 Fig. 2, a detail elevation, looking from the left of Fig. 1 and showing the mechanism whereby the tumbler-shafts and sheet-rolls are operated; Fig. 3, an edge view of the same; Fig. 4, an elevation from the right of Fig. 1. 45 In all these views the connection whereby the sheet-rolls are operated have been shortened, so as to bring them within the limits of the sheet. Fig. 5 is a detail edge elevation showing the construction of the tumblers and the 50 means for operating and holding them; Fig. 6, a front elevation of the same parts; Fig. 7,

a detail section through one of the sheet-rolls, and Fig. 8 a detail vertical section at line *xx* of Fig. 7.

Like numerals denote the same parts in all figures.

1 is the case, preferably divided into three vertical compartments, the central space being adapted to contain the clock, the sheet-rolls, the music-box, and the tumbler-shaft- 60 operating mechanism, and the side space being adapted to contain the tumblers.

2 is the clock, but as its construction and method of operation forms no part of my present invention I have not shown it in detail. 65

3 is a motor, preferably electric, and driven either by a battery or by a connection with some circuit, and this motor is belted to a shaft 4 at the right-hand upper end of the central compartment of the case. By means of pinions the power from this shaft 4 is communicated to a main shaft 5, which extends transversely of the central compartment. Secured 70 upon this shaft and within the frame 6, which provides a support for the tumbler-actuating 75 mechanism, is a cam-disk 7, having in each side thereof a cam-groove 8.

9 are levers fulcrumed upon a shaft 10, mounted in the frame, and each provided with a shoe running in one of the cam-grooves of 80 the disk, so that as said disk revolves the levers will receive an oscillatory movement about their fulcrum. The cam-grooves may be cut in the disk so as to operate the levers simultaneously in the same direction or in 85 opposite directions. At its upper end each of the levers has two outwardly-projecting pins or rolls 11.

12 are shafts of unequal length journaled across the top of the case, (see Fig. 1,) and at 90 their inner adjacent ends they have three outwardly-projecting pins 13, so placed as to be engaged by the pins on the levers at each oscillation, and the shafts thereby turned upon their axes. The operation of these intermeshing pins is somewhat like that of gear-teeth; but as the movement of the shafts is completed by other means it is desirable to have more lost motion than a pair of ordinary geared segments would afford. Upon 95 each shaft immediately over the respective edges of the tumblers are secured two blocks 100

13^a, each provided with outwardly-projecting pins 14, to which the tumbler-chains may be attached, and having also a semicircular open-wire segment 15. In this segment is a 5 small roller 16, traveling therein as on a track, and a cord 17, having a weight 18, extends from said roller over a pulley 19, supported above the plane of the shaft. The object of this segment is to cause the shaft after it 10 has been carried over the center of said segment to be carried the remainder of its throw with a quick sharp action, due to the weight and roll acting on the segment.

Each of the tumblers consists of a rectangular frame 20, whose upper and lower bars are provided with longitudinally-extending grooves 20^a, in which advertisements or pictures may be secured by bending them and allowing their edges to spring into the grooves.

20 Each of the frames is provided with two pins 21 at each end. These pins pass each through a hole in one of a pair of links 22, (see Fig. 5,) and said links being so placed that each hole is in its center. From this comes the arrangement 25 clearly seen at Figs. 5 and 6. The links are each connected so as to form two series by means of chains 23, so that when in the position shown at Figs. 5 and 6 the weight of each segment is supported by two separate and in- 30 dependent chains at each end. Weights 23^a are preferably secured on the ends of the chains for the purpose of causing the chains and frames to hang straight. Upon the same shaft with the cam-disk which operates the 35 levers is secured a ratchet-wheel 24, whose teeth are engaged by a roll 25 on a transverse lever 26, one end of which is pivoted to the frame. The free end of said lever is connected to a downwardly-extending rod 27,

40 which, through a pair of pins or pawls 28, serves at each lifting movement thereof to operate a pair of ratchet-wheels 29 one step. Said ratchet-wheels are secured upon transverse shafts 30, each carrying a sheet-roll 31, 45 composed of the heads 32 and transverse wires 33, extended between the heads. Upon each of these wires is hung a sheet adapted to bear advertising or other matter, as is shown in the Woolverton patent heretofore referred to. In front of each sheet and pivotally attached to its wire at the ends is a wire bail 34, whose function is to accelerate the drop of the sheet after the latter has passed out of the hold of a friction wheel or spring 50 35, which presses against the sheets at the rear of the roller to prevent their falling, except one at a time, as the roller is revolved by the rod operating through the pawls on the ratchet-wheel.

6c In the operation of my invention each revolution of the cam-disk causes the pivoted pin-carrying levers to oscillate about their fulcrum-points, and by their engagement with the pins on the transverse rock-shafts to turn 65 said shafts on their axes. This turns the open-wire segment and raises two of the lines of chains and links, one at each end of the tum-

bler-frames. This turning action also lowers the other two lines of chains and links, and as this occurs the tumbler-frames begin to 70 turn slowly upon their pins. This continues until the roll to which the weight is attached passes the center of the segment, when said weight by its action through the roll completes the throw of the segment by a quick sharp 75 action. This turns all the tumblers completely over, as will be readily understood, since the relative position of the two pairs of links which carry each tumbler has been reversed. This reversal of the tumblers occurs at each 80 rocking movement of the shafts, effected, as heretofore set forth, by the pin-carrying pivoted levers. At each revolution of the ratchet-wheel on the shaft which bears the cam-disk the vertical pawl-rod is lifted once for each 85 tooth on the ratchet by means of the engagement of the latter with the pin on the transverse lever. At each lift of said rod the ratchet-wheels of the sheet-rollers are turned one tooth, and the rollers consequently rotated 90 one step. As a sheet passes from beneath the friction spring or roller the pivoted bail on its wire by bearing against the surface of the sheet serves to pull the latter downward, so as to cause it to fall earlier than it would if 95 in no way assisted. Said sheet having so fallen hangs vertically, with the bail hanging in front of it, until the next sheet falls. As the roller turns, the sheets gradually rise at the rear under the roller or spring, and are 100 there retained until released to fall into view at the front side.

I claim—

1. In an advertising-clock, the combination, with the movement secured within the case, 105 of the rock-shafts journaled upon and extending across the top of the case, the connections between the movement and said rock-shafts, the weights connected with and adapted to complete the movement of the 110 segments, said segments being secured upon the rock-shafts, and the tumblers depending from and operated by means of said rock-shafts, substantially as set forth.

2. In an advertising-clock, the combination, 115 with the rock-shafts journaled upon the top of the case, and the tumblers depending from the outer ends of said rock-shafts and operated thereby, of the movement within the case, a pair of cam-actuated levers adapted 120 to operate the rock-shafts, and the segments and the weights connected thereto, whereby the throw of the rock-shafts in either direction is completed, substantially as specified.

3. In an advertising-clock of the character 125 described, the combination, with the movement arranged within the case, of the cam-actuated levers extending upward from said movement, the rock-shafts journaled upon and extending across the top of the case, the 130 sets of tumblers supported at the sides of the case and operated by said rock-shafts, the pins engaged and adapted to be turned by said levers, and the segments and weights

whereby the completion of the movement of the rock-shafts is accomplished, substantially as set forth.

4. In an advertising-clock of the character described, the combination, with the inclosing-case, of the main shaft 5, extending transversely of said case near its upper end, the disk provided with cam-grooves mounted upon said shaft, and the pivoted levers actuated by said grooves, the transversely-extended rock-shafts journaled on the top of the case and primarily actuated in both directions by said levers, and the weight-operated segments secured upon said shafts, whereby the full throw of the tumblers is insured, substantially as set forth.

5. In an advertising-clock of the character described, the combination, with the rock-shafts, and means, as described, whereby proper axial movement is imparted thereto, of the tumbler-frames suspended from the ends of the rock-shafts, and the independent lines of chains and links pivotally secured to each of said tumblers and adapted to operate the latter to the extent of half a revolution, substantially as set forth.

6. In an advertising-clock of the character described, the combination, with the transversely-extended rock-shafts, and means, as described, whereby the appropriate movement in their bearings is imparted to said rock-shafts, of the lines of tumblers, each provided with two outwardly-projecting pins or trunnions at each end, the links journaled to said trunnions, and the connections between the ends of the several links, whereby the movements of the tumblers are accomplished and said tumblers reversed as to their visual surface, substantially as described.

7. In an advertising-clock of the character described, the combination, with the inclosing-case, of the main shaft and the tumbler-actuating mechanism operated thereby, of a ratchet-wheel carried by the main shaft, a rod lifted by said ratchet, and the sheet-rollers journaled transversely of the case and rotated about their axes by said rod, substantially as set forth.

8. In an advertising-clock, the combination, with the inclosing-case, of the main shaft journaled within said case, the ratchet-wheel carried by said main shaft, a pivoted lever resting upon and reciprocated vertically by the passage of the ratchet-teeth, the rod actuated by the lever, and the sheet-rolls adapted to be rotated step by step by the rod, substantially as set forth.

9. The combination, in a machine as described, with the main shaft, and the sheet-

rolls having transverse wires whereon the 60 sheets are hung, a connection between said shaft and rolls, and pivoted wire bails attached to the wires and adapted to assist the fall of the sheets, as specified.

10. In a machine as described, the combination, with the main shaft, of the cam-disk carried thereby, the transverse rock-shafts and the connection between them and the levers, the tumblers operated by said rock-shaft, the weight-operated segments for assisting 70 the rotation of the shafts, the connecting-rod actuated by the ratchet-wheel on the main shaft, and the sheet-rollers operated step by step by the rod, substantially as and for the purpose set forth.

11. In a machine of the character described, the combination, with the sheet-roll and the means whereby it is operated, of a series of pivoted wire bails carried by said roll, each of said bails contiguous to and adapted to assist the fall of one of the sheets, substantially as set forth.

12. In an advertising-clock or similar machine, the combination, with the series of tumbler-frames, each having its upper and 85 lower bars grooved longitudinally, of the chains whereby said tumbler-frames are suspended and operated, and means, as described, whereby the alternate lifting movements are imparted to said chains, substantially as set 90 forth.

13. In an advertising-clock, the combination, with the primary actuating movement and a suitable inclosing-case, of the rock-shafts journaled at the top of the case, the 95 lines of tumbler-frames depending from said rock-shaft, each of said frames having its upper and lower bars grooved longitudinally, and the independent series of chains and links, each eccentrically connected to each of 100 the tumbler-frames and to the rock-shafts, substantially as set forth.

14. In a machine of the character described, the combination, with a series of rectangular tumbler-frames arranged one above the 105 other, of two pairs of chains, each pair connected to each of said tumbler-frames eccentrically to the center of said frames, and means, as described, whereby said chains are moved vertically in opposite directions and the 110 tumblers thereby reversed, substantially as set forth.

In testimony whereof I affix my signature in presence of two witnesses.

CHARLES ADELBERT WARD.
